T. F. HICKEY.
LEATHER CUTTING MACHINE.
APPLICATION FILED MAY 29, 1919.

1,390,612.

Patented Sept. 13, 1921.

UNITED STATES PATENT OFFICE.

THOMAS F. HICKEY, OF SHREWSBURY, MASSACHUSETTS.

LEATHER-CUTTING MACHINE.

1,390,612.

Specification of Letters Patent. Patented Sept. 13, 1921.

Application filed May 29, 1919. Serial No. 300,511.

To all whom it may concern:

Be it known that I, THOMAS F. HICKEY, a citizen of the United States, residing at Shrewsbury, in the county of Worcester and 5 State of Massachusetts, have invented a new and useful Leather-Cutting Machine, of which the following is a specification.

This invention relates to a machine for cutting sheets of leather into strips of medium width. In a prior application, Serial 10 No. 289,464, filed April 11, 1919, I have shown a machine for cutting leather into narrow strips, which is very effective for the purpose specified, but which is not adapt- 15 ed for cutting wider strips, as the leather will buckle and bulge as it passes through the rolls and uneven edges will result.

It is the object of my present invention to provide a machine which will cut leather 20 into strips of even width, having straight and uniform edges and which will perform this operation easily and rapidly.

With this general object in view, my invention relates to certain arrangements and 25 combinations of parts which will be herein-after described, and more particularly pointed out in the appended claim.

A preferred form of my invention is shown in the drawings in which—

30 Figure 1 is a plan view of my improved machine;

Fig. 2 is a side elevation thereof;

Fig. 3 is an end elevation, and

Fig. 4 is a sectional elevation taken along 35 the line 4—4 in Fig. 1.

Referring to the drawings, my improved machine comprises a frame 10 provided with bearings 11 and 12 for a cutting shaft 13, on which a plurality of cutting disks 14 are 40 mounted in spaced relation, being separated by collars 15. Tight and loose pulleys 16 and 17 are also mounted on the shaft 13.

A shaft 18 is mounted above the cutting shaft 13 and is rotatable in bearings 19 and 45 20, adjustable in the frame 10 and yieldingly supported by compression springs 21. Adjusting screws 22 regulate the distance between the shaft 18 and the cutting shaft 13. The shaft 18 is provided with grooves 23

coöperating with the cutting disks 14. The 50 grooves 23 may conveniently be formed in or between collars on the shaft 18 adapted to be spaced to correspond to the spacing of the cutting disks. A guide flange 24 may also be provided at one end of the shaft 18. 55 The shafts 18 and 13 are connected by gears 25 and 26 through which the shaft 18 is driven.

A pair of feed rolls 27 and 28 are mounted in bearings supported in the frame 10, the 60 rolls being yieldingly pressed together by a spring 29, the tension of which may be adjusted by screws 30.

The rolls 27 and 28 are provided with intermeshing gears 31 and 32 driven from the 65 gear 25 through an idle gear 33. The size of the gears is so related that the surface speed of the feed rolls is somewhat less than the surface speed of the shaft 18 and the disks 14.

The disks 14 and shaft 18 consequently apply constant tension to the stock S during the cutting operation, while the rolls 27 and 28 apply constant pressure to the stock, and deliver it to the cutting disks in smooth and 70 uniform condition, free from irregular folds or curves therein.

A table 34 may be provided for supporting the stock as it is fed to the rolls 27 and 28, and this table may be provided with a 80 guide 35 alined with the flange 24. A second table 36 may also be provided to receive the stock as it leaves the cutting disks 14. The shaft 18 is ordinarily so adjusted that the grooved collars thereon exert no pressure upon the stock S, as the stock passes over the collars on the cutting shaft, but merely coöperate with the disks 14 in performing the cutting operation.

The relatively slow speed of the feed rolls 90 is a very important feature of my invention, and contributes largely to the successful operation of the machine.

Having thus described my invention, it will be evident that changes and modifications can be made therein by those skilled in the art without departing from the spirit and scope thereof as set forth in the claim,

and I do not wish to be otherwise limited to the details herein disclosed, but what I claim is:—

A leather cutting machine comprising a cutting shaft having a series of spaced disk knives thereon, a grooved shaft coöperating with said knives, a pair of feed rolls spaced from said shafts and engaging the stock

as it approaches the knives, and means to drive said cutters at a certain surface speed, ¹⁰ and to drive said feed rolls at a slower surface speed.

In testimony whereof I have hereunto affixed my signature.

THOMAS F. HICKEY.
